CLAIM

The ornamental design for a apple shaped beach blanket with storage pocket, as shown and described.

DESCRIPTION

FIG. 1 is a top plan view of an apple shaped beach blanket with storage pocket showing our new design;

FIG. 2 is a bottom plan view thereof;

FIG. 3 is a front elevational view thereof;

FIG. 4 is a rear elevational view thereof; and

FIG. 5 is a side elevational view thereof, the opposite side being a mirror image of that shown.

FIG. 2

FIG. 3
